DESIGN.

J. E. REIFFENSTINE.

HEATING STOVE.

No. 17,693.

Patented Sept. 6, 1887.

UNITED STATES PATENT OFFICE.

JOHN E. REIFFENSTINE, OF SYRACUSE, NEW YORK, ASSIGNOR TO THE GARLICK PROCESS HEATING COMPANY, OF SAME PLACE.

DESIGN FOR A HEATING-STOVE.

SPECIFICATION forming part of Design No. 17,693, dated September 6, 1887.

Application filed July 27, 1887. Serial No. 245,460. Term of patent 7 years.

To all whom it may concern:

Be it known that I, JOHN E. REIFFENSTINE, of the city of Syracuse, in the county of Onondaga and State of New York, a citizen of the 5 United States, have invented and produced a new and novel Design for Stoves, of which the following is a specification, reference being had to the accompanying photographic drawing, forming a part thereof, and which is an isometrical elevation of the stove complete.

The leading features of my design consist, first, in bay projections upon the sides and front of the stove, each surmounted by a roof with projecting eaves and shingle-work, the 15 bays carrying the doors through which access is had to the interior of the stove; second, in bay projections upon the sides and front of the stove surmounted by a roof with shingle-work and provided with ornamental water-tables subdividing the bays into panels; third, in doors in the upper bay-panels ornamented with an Egyptian design or pattern; fourth, in a lower or ash-pit door in the lower front bay-panel, the front face of which projects downward and outward, creating a foot-rest front of scroll pattern upon the door; fifth, in a top ornament of a central convex medallion with monogram surrounded by a ball-frame in relief, a griffin upon each side of the medallion, disposed head outward, and the two griffins supporting the medallion and frame between them, and a top piece of curved exterior resting upon the medallion-frame, with ball and rectangle ornamentations in relief; sixth, in 35 vertical corners upon the body of the stove, consisting of a part of a square column having a projecting fluted column upon the angle formed by the sides meeting, the sides thereof being ornamented with panels of Egyptian pyramid work in relief upon the top and bottom, and intermediate panels of ball-circle and ball-center work in relief upon a fretted or 40 picked work background.

In the accompanying isometrical elevation (photographic) of the stove complete, 1 represents a side bay, and 2 the front bay, all of the bays being provided with the "chalet" roof 3, with shingle-work, substantially as shown; and 4 5 are the bay water-tables. The 50 double doors 7 close the front bay between the

roof and the water-table 4. These doors and the single door 8, closing the corresponding panel in the side bays, are ornamented with an Egyptian pattern consisting of a horizontal longitudinal cross-bar, a vertical bar on top of 55 the cross-bar, and vertical bars beneath it, forming upper and lower panels, the upper panels being partly closed by the triangles ornamented on front and edge with the ball-in-relief ornaments, and the lower ones by circle-work, substantially as shown.

The doors 9 in the central bay-panels (it may be a solid panel in the side bays) are ornamented with a pattern of leaf-work and horizontal bars, creating irregular-sized rectangular apertures, (or depressions if the side bay-panel is solid,) substantially as shown.

The lower or ash-pit door, 10, consists of a rectangular frame with a plain border, and from the upper side, within the border, the 70 front of the door projects downward and outward, also arching somewhat from one end to the other, creating a projecting and arching surface. The ends of this projecting front are ornamented with a scroll, and the whole projecting door-front constitutes a foot-rest. The 75 side foot-rests, 11, are of the general form of a roll partially unrolled, having rosettes upon the ends of the roll, and the unrolled material is ornamented in open-work with a mixed design of circle-work and block-work. The roll forms the front of the rest, and the ends thereof are supported by brackets in open rectangular bar-work.

The base-skirt 12 is ornamented with an 85 Egyptian pattern of squares and shields in relief upon a fretted or picked work background inclosed within a plain border or frame, with ball or ball-and-cup ornaments pendent from the bottom.

The base-band 13 is ornamented with a pattern consisting of squares created by vertical bars, a circle within each square in relief, balls within each circle, arranged circularly, with a ball-center in relief, a background of fretted 95 or picked work, and a plain border along the top and bottom.

The front and side panels, 14, upon the top of the stove, consist of a plain frame inclosing a pattern in relief, upon a fretted or picked 100

DR

work background, consisting of an open-knotted ribbon in the center, a daisy in full bloom on each side adjacent to the ends, and leaf-work filling.

5 The curved top of the stove in front is subdivided into rectangles by vertical bars, and in each of these rectangles an applique ornament, 15, is placed ornamented with raised edges, a central ball-circle and ball-center in relief upon a fretted or picked work background.

The curved sides 16 of the top of the stove are ornamented with diamond-shaped openings extending either clear across the sides or 15 partly across, with an applique square at each end of the same pattern as those upon the curved front.

The top ornament, 17, is fully described in subdivision 13 above.

20 The base-band corners 18 are ornamented with a projecting columnar design, substantially as shown.

The vertical corners 19 of the body of the stove, and also upon the top portion, 21, above 25 the main water-table, are fully described in the subdivisions 15 and 16 above.

The panels 20, composing the roof-ridge ornaments, are fully described in subdivision 17 above.

30 The bay water-tables 4 and 5 are ornamented with relief-work consisting of cups with a ball in the center of each cup.

It will be observed that the circle and circle-and-ball work, the rectangles or squares, 35 the pyramids, and scroll or roll work are prominent features of my design, and also that leaf-work is a feature.

What I claim as my invention, and desire to secure by Letters Patent, is—

40 1. The design for a stove herein shown and described, consisting of a rectangular base and a rectangular body provided with front and side bays surmounted by a shingle-work roof with projecting eaves, as described and shown.

2. The design for a stove herein shown and 45 described, consisting of a rectangular base and a rectangular body provided with front and side bays surmounted by a roof with shingle-work.

3. In a design for a heating-stove, doors 78, 50 herein shown and described, consisting of a frame provided with bars, creating rectangular openings, with circle open-work in the lower openings and triangles extending upward into the upper openings, as described 55 and shown.

4. In a design for a heating-stove, a stove-door, 10, consisting of a rectangular frame inclosing an ornamental front projecting outward and inclining downward to a scroll, as 60 described and shown.

5. In a design for a heating-stove, a top ornament consisting of a central convex medallion with monogram in relief inclosed by a ball-frame in relief, a griffin upon each side of 65 it, heads outward and supporting the medallion-frame, and a top of curved exterior, with ball and rectangle ornaments, substantially as shown and described.

6. In a design for a heating-stove, the vertical corners 19, consisting of part of a square column having a projecting fluted column upon the angle, the sides being ornamented with pyramid-work upon the ends, and intermediate ball-circle and ball-center work in relief upon 75 a fretted background, as shown and described.

7. In a design for a heating-stove, the vertical corners of the body, consisting of part of a square column having a projecting fluted column upon the angle, as shown and de- 80 scribed.

In witness whereof I have hereunto set my hand this 6th day of May, 1887.

JOHN E. REIFFENSTINE.

In presence of—

C. W. SMITH,

CHARLES GARLICK.
